UNITED STATES PATENT OFFICE

2,446,585

WOOD SPLITTING MACHINE

Cleiburn T. Hanners, Etna, Calif.

Application April 13, 1945, Serial No. 588,154

2 Claims. (Cl. 144—193)

1

The present invention relates to new and useful improvements in machines for splitting wood, and more particularly to a machine of this character for splitting sawed blocks into kindling and other portions suitable for stove and other use.

An important object of the present invention is to provide a slidably mounted wood-splitting blade together with means for reciprocably actuating the blade toward and away from the wood to be split, together with means for regulating the force of the splitting action of the blade.

A further object of the invention is to provide means for controlling the forward and backward movement of the wood-splitting blade or head at all times.

A still further object is to provide a machine of this character of simple and practical construction, which is strong and durable, efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a side elevational view with parts broken away and shown in section.

Figure 2 is a top plan view.

Figure 3 is a fragmentary side elevational view showing the drive means for the reciprocating cutter or splitting head.

Figure 4 is a transverse sectional view taken substantially on a line 4—4 of Figure 1.

Referring now to the drawing in detail, wherein for the purpose of illustration I have disclosed a preferred embodiment of the invention, the numeral 5 designates generally the supporting frame or base of the machine on which is supported a table 6 by means of legs or uprights 7. At one end of the table 6 is provided an upstanding anvil or stop 8 against which one end of the block of wood to be split is placed, the wood lying on the table 6.

A drum 9 is secured to a shaft 10 extending transversely beneath the table, the shaft being journaled on the lower end of hanger bearings 11 which are swingably supported at their upper ends in pins 12 secured to frames 13 at the under side of the table 6.

An elongated blade or splitting member 14 is slidably mounted on the table 6, one end of the member being provided with a sharpened cutting

2

head 15 adapted for movement toward and away from the anvil 8.

A cable 16 has its intermediate portion wound on the drum 9 and its ends extending oppositely therefrom above and below the drum, one end of the cable extending forwardly under the table 6 for attaching to the under side of the splitting member 14 adjacent the head 15 thereof by means of an eye bolt 17 extending vertically through the splitting member.

The other end of the cable extends rearwardly under the table and is inserted through an eye bolt 18 attached to the rear of the splitting member 14 and is provided with an adjusting screw 19 including a nut 20 threaded thereon and a coil spring 21 positioned between the nut and the rear side of the eye bolt 18, as shown to advantage in Figure 1 of the drawing, whereby to adjust the tension of the cable.

The table 6 is formed with a longitudinally extending slot 22 to accommodate the eye bolts 17 and 18 during the reciprocating movement of the cutting member 14 thereon.

To one end of the shaft 10 is secured a friction bull wheel 23 and the shaft 10 is rockably actuated to move the bull wheel 23 bodily forwardly and rearwardly by means of a link 24 pivoted at one end to the shaft 10 and extending forwardly and pivotally attached at its front end adjacent the lower end of a lever 25 which is pivoted on a pin 26 at its lower end and extends vertically at one side of the table 6. The lever 25 is secured in its intermediate, or in a forward or rearward position by means of a spring catch 27.

The bull wheel 23 is positioned between front and rear friction wheels or rollers 28 and 29, the friction wheel 28 being secured at one end of a transversely extending shaft 30 journaled on the frame 5 and to the other end of which is secured a pulley or sprocket 31 about which a belt or chain 32 is trained and extends over upper end lower idler pulleys or sprockets 33 for rotating the shaft 30 in an opposite direction by means of a pulley or sprocket 34 secured at the end of a shaft 35 to which the rear friction wheel 29 is also secured.

The shaft 35 is driven by a belt or chain 36 from a motor-driven shaft 37, the motor (not shown) being of any conventional form.

A belt or chain tightener 38 is provided for the upper flight of the belt or chain 32, as shown to advantage in Figure 3 of the drawing.

In the operation of the device, the bull wheel 23 is normally held out of frictional driving engagement with either of the drive wheels 28 and

29 by securing the lever 25 in its neutral position, as shown in Figure 1 of the drawing.

The friction drive wheels 28 and 29 rotate in opposite directions, as shown by the arrows in Figure 1 of the drawing, and by manipulating the lever 25 to move the bull wheel 23 forwardly and rearwardly, the bull wheel will likewise be selectively driven in opposite directions to thus wind and unwind the respective ends of the cable 16 and reciprocate the splitting member 14 which thereby will move the splitting head 15 toward and away from the anvil or stop 8 for splitting the block of wood lying on the table 6 and held against the anvil.

By reason of the frictional drive connection for the bull wheel 23, it will be apparent that the speed or force of the splitting head 15 may be regulated by the pressure exerted on the lever 25.

While I have herein shown and described a preferred embodiment of the invention, it will be understood that various changes may be made in the construction and arrangement of the parts without departing from the spirit of the invention or the scope of the appended claims.

Having thus described the invention, what I claim is:

1. A log splitting machine comprising a table adapted for supporting a log to be split thereon, an anvil rising above the table and forming an abutment for one end of the log, an elongated splitting member having a splitting head at one end, said splitting member being slidably mounted on the table, a drum having a cable wound thereon with its ends extending in opposite directions from the cable and attached respectively to the front and rear ends of the splitting

member, a swingable support for the drum, a friction wheel secured to the drum for rotation therewith, a pair of oppositely rotating friction drive wheels, and means for moving the first-named friction wheel into and out of engagement with said friction drive wheels to reciprocably actuate the splitting member.

2. A log splitting machine comprising a table adapted for supporting a log to be split thereon, 10 an anvil rising above the table and forming an abutment for one end of the log, an elongated splitting member having a splitting head at one end, said splitting member being slidably mounted on the table, a drum having a cable wound thereon with its ends extending in opposite directions from the cable and attached respectively to the front and rear ends of the splitting member, a swingable support for the drum, a friction wheel secured to the drum for rotation therewith, a pair of oppositely rotating friction drive wheels, and a manually operable lever connected to said first-named friction wheel and adapted for moving the same bodily into and out of engagement with the respective friction drive wheels for reciprocably actuating said splitting member.
